US0D1079664S

(12) **United States Design Patent** (10) Patent No.: **US D1,079,664 S**
(45) Date of Patent: ** Jun. 17, 2025

(54) **MOBILE PHONE**

(71) Applicant: **HUAWEI TECHNOLOGIES CO., LTD.**, Guangdong (CN)

(72) Inventors: **Sylvain Gerber**, Paris (FR); **Wenjing Sun**, Paris (FR); **Yang Wan**, Shenzhen (CN); **Jinghao Wang**, Paris (FR); **Yi Liu**, Shenzhen (CN)

(73) Assignee: **HUAWEI TECHNOLOGIES CO., LTD.**, Shenzhen (CN)

(**) Term: **15 Years**

(21) Appl. No.: **29/879,528**

(22) Filed: **Jul. 10, 2023**

(30) **Foreign Application Priority Data**

Jan. 10, 2023 (CN) 202330015883.3
